Inventor:

Robert Dutch

United States Patent Office.

ROBERT DUTCH, OF JERSEY CITY, NEW JERSEY.

Letters Patent No. 92,592, dated July 13, 1869.

IMPROVED RAILWAY-CAR AXLE.

The Schedule referred to in these Letters Patent and making part of the same.

To all whom it may concern:

Be it known that I, ROBERT DUTCH, of Jersey City, county of Hudson, and State of New Jersey, have invented a new and useful Improvement in Journals for Railroad-Trucks; and do hereby declare that the following is a general description thereof, reference being had to the accompanying drawings, making part of this specification, of which—

Figure 1 is a plan or top view;

Figure 2, a longitudinal section of same; and

Figure 3, a view of a section of the journal, as removed from its socket or case.

The nature of my invention consists in the construction and arrangement of the divided axles, each with two separated flanges, in combination with coupling-tubes, having enclosing-heads, substantially as herein-after set forth, for the purpose of enabling the outer truck-wheels of a car or engine to perform a greater number of revolutions than the inner truck-wheels, when travelling on a railroad-curve, thereby regulating the centrifugal force of an engine and train of cars while in rapid transit on the rails.

In the drawings—

A indicates the journal, or axle of a railroad-truck, formed in two sections, B B, and having feet c c, which abut against each other, and collars, or shoulders d d, which abut against the outer ends of their enclosing-

case, while the shafts e e of the journal extend through said case, (see fig. 2,) for reception of the truck-wheels.

F is the socket, or case of the journal, made in two sections g g, and having flanges h h, by means of which the socket-sections are firmly secured and bolted together by bolts i i, &c.; and k k are stops which confine the journal in its enclosing-case, and against which the collars d d of the journal rest.

The flanges of the socket-case may contain male and female screws, for connecting the socket-sections in addition to the bolts, for further security, if desired.

The socket, or case F is sustained in bearings attached to the railroad-truck, and revolves within said bearings, while the journal A, carrying the truck-wheels, revolves within the said case F, by means of which the wheels revolve independently of each other.

What I claim as my invention, and desire to secure by Letters Patent, is—

The construction and arrangement of the divided axles A A, each with two flanges c d, in combination with the coupling-tubes F F, having heads k k, substantially as and for the purpose herein specified.

In testimony whereof, I have hereunto set my signature, this 29th day of December, A. D. 1868.

ROBERT DUTCH.
